UNITED STATES PATENT OFFICE.

CHARLES A. DUEPNER, OF MINNEAPOLIS, MINNESOTA, ASSIGNOR TO THE M. J. GRADY
FIXTURE MFG. CO., OF MINNEAPOLIS, MINNESOTA, A CORPORATION OF MINNESOTA.

DESIGN FOR A LIGHTING-FIXTURE.

49,113.

Specification for Design.

Patented May 30, 1916.

Application filed April 22, 1916. Serial No. 93,029. Term of patent 3½ years.

To all whom it may concern:

Be it known that I, CHARLES A. DUEPNER, a citizen of the United States, residing at Minneapolis, in the county of Hennepin and State of Minnesota, have invented a new, original, and ornamental Design for a Lighting-Fixture, of which the following is a specification, reference being had to

the accompanying drawing, forming part thereof.

The figure is a side elevation of a lighting fixture, showing my new design.

I claim:

The ornamental design for a lighting fixture, as shown.

CHARLES A. DUEPNER.
